UNITED STATES PATENT OFFICE.

JOHN E. SHARPE, OF ONEIDA, NEW YORK, ASSIGNOR OF ONE-HALF TO
NEWTON D. BARTLE, OF GUILFORD, NEW YORK.

INSULATOR-SUPPORTING ARM.

SPECIFICATION forming part of Letters Patent No. 700,570, dated May 20, 1902.

Application filed December 26, 1901. Serial No. 87,215. (No model.)

To all whom it may concern:

Be it known that I, JOHN E. SHARPE, a citizen of the United States, and a resident of Oneida, in the county of Madison, in the State 5 of New York, have invented new and useful Improvements in Insulator-Supporting Arms, of which the following, taken in connection with the accompanying drawings, is a full, clear, and exact description.

10 This invention relates to the construction of the arm which is fastened transversely to an erected pole and supports on its top the insulators, which carry electric wires stretched across said arm.

15 The object of this invention is to provide an insulator-supporting arm which shall be superior in strength and durability, and shall present minimum surface for lodgment of snow and ice upon it, and shall also afford a 20 convenient and permanent hold for the attachment of the insulator; and to that end the invention consists in the improved construction of the insulator-supporting arm hereinafter described, and set forth in the 25 claims.

In the accompanying drawings, Figure 1 is a side view of an insulator-supporting arm embodying my invention. Fig. 2 is an end view of said arm detached from its supporting-pole. Fig. 3 is a vertical section on line XX in Fig. 1, and Fig. 4 is an inverted plan view of the aforesaid arm.

Similar letters of reference indicate corresponding parts.

35 *a* represents the arm, which is fastened transversely to the erected pole *P* and carries upon its top the insulator *C*, which latter is shown of the form described and claimed in my Letters Patent No. 679,544, of July 30, 1901; 40 but my present invention is not limited to the use of that or any other style of insulator. My present invention resides in the novel construction of the supporting-arm *a*, which I form of a prolonged plate of iron or steel, 45 preferably formed by means of rolls of a rolling-mill, which produces a plate bent transversely and formed with a central seat or horizontal portion *b* and with parallel flanges *c c*, depending from the edges of said central portion, and thus providing the arm *a* with a 50 longitudinal cavity *d* in its under side. The

bottom of said cavity being open prevents water, snow, ice, and dust from collecting in the arm *a*. The flanges of that portion of the said arm which is attached to the pole *P*, 55 I prefer to form vertical or parallel, as shown at *c'*, to permit of readily placing in the cavity *d* a filling-block *g* and to allow the arm to be properly seated in the boxing or recess *e*, cut into the side of the pole *P*, as shown in 60 Fig. 3 of the drawings.

The arm *a* is attached to the pole *P* by means of bolts *f*, passing through perforations in the vertical portions of the flanges *c* and either screwed into the pole, as represented 65 in Fig. 3 of the drawings, or passing through the pole and provided with nuts on their protruding ends. To prevent said vertical portions *c'* of the flanges from being crushed inward by the pressure exerted thereon in 70 tightening the bolts *f*, I interpose between them the aforesaid filling-block *g*, of suitable hard material, to effectually stay the flanges. The flanges *c c* of the remaining or free end portions of the arm *a* I prefer to compress, 75 so as to form them converging or inclined toward each other, and thus brace them.

In attaching to the arm *a* the insulator *C* of the form shown in Figs. 1 and 2 of the drawings or of any other form requiring attaching-bolts *h* passing vertically through the said arm I place across the bottoms of the two flanges *c c* a bar or washer *i* and preferably provide the ends of said bar or washer with shoulders *i' i'*, which engage the outer 85 sides of the flanges, as illustrated in Figs. 1 and 2 of the drawings. Said shoulders serve to lock the bar or washer on the arm *a*. The bars or washers *i i* are perforated and receive through them the attaching-bolts *h h*, which 90 pass through perforated feet on the legs *l l*, attached to the insulator and resting upon the seat or horizontal portion *b* of the arm *a*. The lower ends of the bolts *h* are screw-threaded and provided with nuts *n*, which bear on 95 the under side of the bar or washer *i* and fasten the insulator to the arm.

What I claim as my invention is—

1. An insulator-supporting arm consisting of a prolonged metallic plate formed transversely with a horizontal central portion and with stiffening-flanges depending from the 100

edges of said central portion, in combination with an insulator mounted on the horizontal central portion of the arm, bars disposed across the bottom of the arm and bearing on the bottom edges of the flanges, and bolts tying the insulator to said bars.

2. An insulator-supporting arm consisting of a prolonged metallic plate formed transversely with a horizontal central portion and with longitudinal flanges depending from the edges of the central portion, bars disposed across the bottom of the flanges and provided with shoulders engaging the sides of the flanges, and bolts tying the insulator to said bars as set forth.

3. An insulator-supporting arm consisting of a prolonged metallic plate formed transversely with a seat in its center and with longi-

tudinal flanges depending convergently from the edges of the seat, in combination with the insulator mounted on said seat, bars disposed across the bottom of the flanges, and bolts tying the insulator to said bars.

4. As an improved article of manufacture, an insulator-supporting arm formed of a prolonged metallic plate bent transversely into the shape of flanges depending from a straight central portion, the flanges of the attaching portion of the arm being parallel and the flanges of the free end portions being converging downward as set forth and shown.

JOHN E. SHARPE. [L. S.]
